UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

OIL-STOVE.

1,276,872.

Specification of Letters Patent. Patented Aug. 27, 1918.

Application filed August 8, 1914. Serial No. 855,861.

To all whom it may concern:

Be it known that I, LEE S. CHADWICK, a citizen of the United States, residing at East Cleveland, in the county of Cuyahoga and State of Ohio, have invented a certain new and useful Improvement in Oil-Stoves, of which the following is a full, clear, and exact description, reference being had to the accompanying drawings.

10 This invention relates to oil stoves which are designed for use with liquid fuel and which, while capable of operation under more general conditions of use, are particularly well adapted for the burning of such fuel in places exposed to drafts and with the maintenance of a smokeless flame. Liquid fuel stoves possessing this capacity of operating when exposed to strong drafts are particularly useful as so called "orchard heaters." It is the general object of this invention to produce a stove of this kind which, while being particularly efficient in operation, will be at the same time extremely economical of production; also to 25 produce a stove of this character which is simple in construction, involving a minimum number of parts, and which can be readily assembled and disassembled for purposes of packing and shipping; also to 30 produce a stove of this character which may be conveniently replenished with fuel from time to time as occasion may require and one which is particularly easy to clean and to maintain in operation. Further and more 35 limited objects will appear hereinafter in connection with the detailed description and will be embodied in the combinations of elements set forth in the claims forming part hereof.

40 In the drawings, Figure 1 represents a central vertical sectional view through a heater constructed in accordance with my invention; Fig. 2 is a plan view of the heater shown in the preceding figure, the shield and extinguisher hood being removed and a part of the upper burner cap being broken away to reveal the construction therebeneath; and Fig. 3 is a detail in perspective of a part of the wick raising 45 and lowering band.

50 Describing by reference characters the various parts illustrated herein, 1 denotes the outer wall, 2 the bottom wall, and 3 the inner wall of an open-top annular reser-

voir. The outer wall and the bottom wall 55 may be conveniently formed from a single sheet of metal and the inner wall may be connected to the bottom wall in any approved manner, as indicated at 4. This inner wall extends upwardly, preferably a 60 little higher than the outer wall, where it is bent inwardly to form a horizontal shoulder, as shown at 5, thence upwardly to form a cylindrical wall 6. Above the cylindrical wall 6, the metal from which the parts 3-6 65 are formed may be extended horizontally across the top of the space inclosed by the wall 3, to form a cap 7, the cap being shown as provided with a plurality of perforations 8.

70 The burner which is to be used in connection with the stove is of the perforated commingling tube type, and the inner tube 9 may be conveniently seated upon the shoulder 5, fitting about the cylindrical wall 6, to which it may be permanently secured, as by "peening" together the contiguous portions of the wall 6 and the commingling tube 9, as indicated at 10. The inner commingling tube is of a height sufficient to insure proper combustion and is shown as closed at its top by a cap 11, which may be united to the upper end of the tube in any approved manner.

75 The bottom of the reservoir is provided with any suitable support which will elevate it to the desired height to admit air to the central tube 3. In the drawing, legs 12 are shown as used for this purpose, and said legs may be conveniently formed by metal straps 80 bent to appropriate shape and secured to the bottom and to the outer wall of the reservoir, as by rivets 13.

85 The second part of the stove consists generally of the annular cover 14 having thereon the outer commingling tube, a protecting hood or shield (when such is required) and the outer wick tube, the wick and wick raiser (to be described hereinafter) being associated in this case with the reservoir- 90 assembly. The cover 14 is shown as provided with a depending flange 15 forming a skirt overhanging the upper wired edge of the reservoir therebeneath. Between its outer and inner peripheral portions, the 95 cover is shown as provided with a plurality of angular straps the bottoms of which may be secured to the cover in any approved 100 105

manner, as by being fitted within depressions 16 therein, the upwardly and inwardly projecting portions 17 of the straps supporting a frusto conical hood 18, constituting a shield extending above the tops of the commingling tubes. The base of the hood or shield is preferably substantially flush with the surface of the portion of the cover therewithin, such portion of the cover being 5 preferably projected upwardly into an annular ring or corrugation, as shown at 19. The inner edge portion of the cover is shown as projected downwardly to form a cylindrical wall 20, thence inwardly to form a 10 horizontal ledge 21, thence downwardly to form a short cylindrical wall 22, which cylindrical wall may be secured to the outer wick tube 23 in any approved manner. The wick tube 23, when the parts are in the operative relation to each other shown in Fig. 15 20, preferably projects above the inner wick tube and is shown as provided at its top with a series of inwardly projecting fingers 24 constituting a stop for the upper edge 25 of the wick. The bottom of this outer wick tube terminates a considerable distance above the bottom of the reservoir and is flared outwardly, as shown at 25, to provide with the adjacent portion of the inner tube 20 30 3 a flaring mouth for the wick. The seat provided by the wall 20 and ledge 21 is adapted to receive the outer perforated commingling tube 26, which may be secured to the wall 20, if desired, as by peening together the overlapping metal parts. 35

27 denotes the wick, which is inserted in the wick space provided between the tubes 3 and 23. This wick is preferably of considerably less thickness than the width of 40 the space between said tubes, and the upper and outer surface of the wick is engaged by a carrier band of peculiar construction. This band is a continuous annular band 28 which is of such diameter as to extend about 45 the upper portion of the wick and at the same time provide a free clearance space with the outer wick tube. The band is in effect a segmental band, the segments being shown as provided by and between angular 50 metal strips, one flange 29 of each angle strip projecting inwardly and preferably radially, the other flange 30 affording means by which the strip may be secured to the ring in any suitable manner, as by riveting 55 or soldering. In the drawing, four such strips are provided, whereby the band is divided into four segments, but it will be evident that the number of strips and segments may be varied to suit the requirements 60 of any particular installation. The wick raising band is provided with a plurality of inwardly projecting spring fingers 31, which may be conveniently cut from the metal of the band and which are adapted 65 to press against and into the outer surface

of the wick and form a means of engagement between the wick and the band whereby the wick may be raised and lowered through the corresponding movement of the band. At its upper end, the band is shown 70 as provided with inwardly projecting fingers 32, which serve as a stop for the top of the wick. For the purpose of raising and lowering the band, a bail 33 is provided, said bail extending upwardly in the space 75 between the commingling tubes 9 and 26 and above and across the cap 11 of the inner commingling tube. The connection between the bail and the ring may be conveniently made by means of upwardly projecting straps 34, formed from the metal of the band and of about the same gage as said metal to which the lower ends of the bail may be suitably secured. The ring 28 is shown as provided with a suitable number 80 of perforations 35.

The segmental feature of the ring permits the employment of a built-up or segmental wick formed from a number of independent wicks, each of suitable width to fit 90 between adjacent ribs or flanges 29. It also permits of a convenient regulation of the size of the flame and a consequent regulation of the heat evolved from the stove. If it is desired to operate the burner at less than 95 maximum capacity, one or more of the wick segments may be pulled downwardly below the fingers 32 so as to be out of operative relation when the wick band is elevated. The burner will then operate with the vapor 100 evolved from the remaining segment or segments. When it is desired to operate the burner at full capacity, all of the wick segments will be abutted against the stop fingers 32 whereupon, when the band 28 is elevated against the stops 24, the burner will 105 operate at full or maximum capacity.

As in the case with my application No. 855,462 filed August 6, 1914, the stove consists essentially of two assemblies, one assembly being constituted by the open-top reservoir with its attached inner wick tube, the inner commingling tube, the wick, and wick raising band and bail, and the other assembly being constituted by the removable 115 cover carrying the outer commingling tube and also (when necessary) the shield 18. When it is desired to extinguish the flame or to protect the burner parts against rain or other weather conditions, an extinguisher 120 hood 36 may be employed, said extinguisher hood being preferably frusto-conical in shape and sufficiently larger than the shield 18 to extend above and about the same. Prior to applying this extinguisher hood, the 125 wick will have been lowered through the bail and the bail thereby moved downwardly a sufficient distance to receive thereabove the top of the extinguisher hood.

When it is desired to fill the reservoir, it 130

is necessary only to remove or tilt the cover 14, which will enable the operator to pour the liquid fuel directly into the reservoir without any funnel or special filling appliance. The wick may be lighted when the cover is thus removed or tilted, or the wick 5 may be ignited by means of a hydrocarbon igniter, whereby burning fuel, such as gasoline, may be dropped into the top of the 10 space between the wick tubes. When it is desirable or necessary to clean the commingling tubes, this operation may be performed in a particularly convenient manner, by removing the cover whereby the inner surface 15 of the outer tube and the outer surface of the inner tube will be exposed for the application of a brush or any other suitable article. The wick band with its attached wick segments may be applied when the cover and 20 its attached parts are removed.

The stove or heater shown herein is extremely efficient in operation, not only in its ability to effectually heat the surrounding atmosphere but in its immunity from smoke 25 and from extinguishment and serious interference by drafts. With a heater such as disclosed herein it is possible to heat an orchard efficiently without damaging the fruit and without the necessity of washing the 30 fruit for removing therefrom the carbon stains which will be deposited thereon by a smoky flame. Furthermore, the burner, while not dependent upon any fine and impractical mode of adjustment for regulating 35 the heat, may nevertheless be adjusted in a convenient and efficient manner to secure such variation in capacity as will adapt it for all ordinary incidents of use, and this regulation can be effected in a convenient 40 and practical manner.

While the possession of the advantages referred to hereinbefore necessarily makes the heater peculiarly efficient as an "orchard heater", I wish to be understood as not limiting 45 my invention to this one use, since, because of its efficiency and freedom from smoke, it is applicable to the heating of water, the heating of garages and other inclosed spaces, and is generally useful wherever 50 efficient heating is desired.

While I have described my invention in detail in connection with the embodiment illustrated herein, it is to be understood that I do not thereby limit my invention to such 55 details of construction and that these details may be varied, or departed from, more or less without avoiding the spirit of my invention.

Having thus described my invention, what 60 I claim is:—

1. In a stove of the character described, the combination of an open top reservoir having an inner wick tube and a perforated inner commingling tube, a removable cover 65 for the reservoir having a depending outer

wick tube adapted to surround the inner wick tube and an outer perforated commingling tube, a wick in the space, between said wick tubes, and a wick raiser connected with said wick and having an operating device 70 extending upwardly between the commingling tubes and across the top of the inner commingling tube.

2. In a stove of the character described, the combination of an inner wick tube, an outer wick tube, commingling tubes extending above the wick tubes, a wick in the space between said wick tubes, and a wick raiser for the wick having an operating portion extending upwardly between the commingling 80 tubes and across the top of the inner commingling tube.

3. In a stove of the character described, the combination of an open top reservoir having a wick tube, a wick surrounding the 85 wick tube, a wick band applied to the exterior surface of the wick and having an upwardly projecting operating device connected thereto, a removable cover for the reservoir, and a wick tube depending from said 90 cover and adapted to surround the first mentioned wick tube and form a wick space therewith.

4. In a stove of the character described, the combination of an open top reservoir 95 having an inner wick tube, a wick surrounding said tube, a band surrounding the wick, an operating device connected with said band and projecting upwardly therefrom, a removable cover for the top of the reservoir, 100 an outer wick tube depending from said cover and adapted to surround the inner wick tube and inclose the wick therebetween, and means projecting inwardly from the outer wick tube and adapted to limit the 105 movement of the wick.

5. In a stove of the character described, the combination of an open top reservoir having an inner wick tube, a wick surrounding said tube, a removable cover for the top 110 of the reservoir, an outer wick tube depending from said cover and adapted to surround the inner wick tube and form a wick space therewith, and fingers projecting inwardly from the top of the outer wick tube 115 adapted to engage the top of the wick to limit the movement thereof.

6. In a stove of the character described, the combination of an open top reservoir having an inner wick tube and a perforated 120 commingling tube above said wick tube, a wick surrounding the inner wick tube, a band applied to the outer surface of said wick, a bail projecting upwardly from said band and extending across the top of the 125 commingling tube, a removable cover for the top of the reservoir, said cover having an outer wick tube depending therefrom and adapted to surround the inner wick tube, said outer tube being provided with in- 130

- wardly projecting fingers at its top constituting stops for the wick, and an outer perforated commingling tube carried by the cover and extending upwardly from the 5 outer wick tube.
7. In a stove of the character described, the combination of an open top reservoir having an inner wick tube and a perforated commingling tube above said wick tube, a 10 wick surrounding the inner wick tube, a band applied to said wick, an operating device connected to said band and, extending alongside the commingling tube, a removable cover for the top of the reservoir, said 15 cover having an outer wick tube depending therefrom and adapted to surround the inner wick tube, and an outer perforated commingling tube carried by the cover and extending upwardly from the outer wick tube.
10. In a stove of the character described, the combination of a reservoir having an open top and a vertical wick tube extending therethrough, a perforated inner commingling tube extending above the first mentioned tube, a cover removably applied to the reservoir, a tube depending from the cover and surrounding the first mentioned tube and forming therewith an annular wick space, a series of fingers projecting from one of the 25 wick tubes and forming a wick stop, a wick in the wick space, an outer commingling tube extending upwardly from the upper end of the tube carried by the cover, and a wick raiser having operating means above 30 the inner commingling tube for raising and lowering said wick.
9. In a stove of the character described, the combination of a reservoir having an open top and a vertical wick tube extending therethrough, a perforated inner commingling tube extending above the first mentioned tube, a cover removably applied to the reservoir, a tube depending from the cover and surrounding the first mentioned 40 tube and forming therewith an annular wick space, a series of fingers projecting from one of the wick tubes and forming a wick stop, a wick in the wick space, an outer commingling tube extending upwardly from the upper end of the tube carried by the cover, and an adjustable device for retaining said 45 wick at various elevations along the inner wick tube.
10. In a stove of the character described, the combination of a reservoir having a wick tube therewithin, a perforated inner commingling tube extending above the first mentioned tube, a cover removably applied to the reservoir, a wick tube depending from 55 the cover and surrounding the first mentioned tube and forming therewith an annular wick space, a wick stop carried by the cover, a wick in the space between the wick tubes, an outer commingling tube extending 60 upward from about the upper end of the 65 outer wick tube, and wick adjusting mechanism for retaining the wick at various elevations against said inner wick tube.
11. In a stove of the character described, the combination of a reservoir having an 70 open top and a vertical tube extending therethrough, a perforated inner commingling tube extending above the first mentioned tube, a removable cover for the top of said receptacle having an opening and a tube 75 projecting downwardly from said opening and forming with the first mentioned tube an annular wick space, an outer perforated commingling tube projecting upwardly outside the depending tube, a wick in the wick 80 space, a wick-engaging device for said wick, a pair of diametrically opposed straps connected with said device and projecting into the space between the commingling tubes, and operating means connected with said 85 straps.
12. In a stove of the character described, the combination of an open top reservoir having a vertical tube extending therethrough, a perforated inner commingling 90 tube extending above the wick tube, a wick surrounding the wick tube, a wick band applied to the wick, a bail connected to said wick band and extending upwardly and across the top of the commingling tube, a removable cover for the reservoir, a wick tube depending from said cover and forming with the first mentioned wick tube an annular wick space, said tube having one or more 95 stops at its top adapted to limit the raising 100 movement of the wick, and a perforated outer commingling tube carried by the cover and extending above the wick tube.
13. In a stove of the character described, the combination of an inner and an outer 105 wick tube, a wick band in the space between said tubes, and a wick operatively connected to said band, said wick comprising a plurality of wick segments at least one of which is vertically adjustable with respect to said 110 band.
14. In a stove of the character described, the combination of an inner and an outer wick tube, a wick band in the space between said wick tubes, and a wick operatively connected to said band, said wick comprising a plurality of wick segments, at least one of said segments being vertically adjustable with respect to said band, and operating 115 means connected with said band whereby the 120 wick assembly may be raised and lowered.
15. In a stove of the character described, the combination of an inner and an outer wick tube, a band mounted in the space within said wick tubes, said band being divided 125 into a plurality of segments by vertically extending ribs or flanges, wick segments applied to the band between the ribs or flanges, and wick engaging means carried by the band between each pair of ribs or flanges, 130

whereby the tops of the wick segments may be adjusted with reference to each other thereby to vary the effective vapor generating space at the top of the complete wick.

5 16. In an oil stove, the combination of inner and outer wick tubes, a wick band in the space between said tubes, said band being divided into a plurality of cylinder segmental sections, a plurality of wick segments corresponding to the band sections and interposed between the wick band and one of the wick tubes, at least one of said wick segments being vertically adjustable with respect to said band thereby to render one or 10 more segments of the wick inoperative for vaporizing purpose when it is desired to operate the stove at less than full capacity.

15 17. In an oil stove, the combination of inner and outer wick tubes, a wick band interposed in the space between said tubes, a wick comprising a plurality of wick segments interposed between the wick band and one of the wick tubes, at least one of said segments being vertically adjustable with 20 reference to said band.

25 18. In an oil stove, the combination of inner and outer wick tubes, a segmental wick band therebetween, a plurality of wick segments corresponding to the wick band segments and interposed between the wick band and one of the wick tubes, at least one of said wick segments being adjustable with 30 reference to the top of the band, thereby to correspondingly vary the effective vaporizing area at the top of the wick, and means for raising and lowering said wick band.

35 19. In an oil stove, the combination of inner and outer wick tubes, a wick band therebetween and a plurality of wick segments interposed between the wick band and one of the tubes and independently adjustable in the space between the band and the wick tube whereby the effective vaporizing area at the top of the wick may be varied.

45 20. In an oil stove, the combination of inner and outer wick tubes, a segmental wick band therebetween, a plurality of wick segments corresponding to the band segments and interposed between the band and one of the wick tubes, and stops carried by the wick band and located in substantially the same horizontal plane for limiting the elevation of the wick segments, at least one of the wick segments being adjustable with 50 reference to said stops thereby to vary the vapor generating capacity of the wick.

55 21. In an oil stove, the combination of inner and outer wick tubes, a wick band therebetween, a plurality of wick segments interposed between the band and one of the wick tubes, said wick segments being vertically adjustable, and a common stop device which determines the maximum elevation of the wick segments.

65 22. In an oil stove, the combination of

inner and outer wick tubes, a segmental wick band in the space between said tubes, said band having a plurality of wick stops arranged in a common horizontal plane, a plurality of wick segments corresponding to the band segments and adapted to be engaged by the stops at their upper ends thereby to limit their vertical adjustment with reference to the band, said wick segments being independently adjustable with reference to said stops, a raising and lowering device connected to said band, and one or more stops extending over the space between the wick tubes from an adjacent part of the stove and arranged to limit the elevation of the band.

70 23. In an oil stove, the combination of inner and outer wick tubes, a wick band in the space between said tubes, a plurality of wick segments interposed between said band and one of the tubes, at least one of said segments being vertically adjustable, a raising and lowering device connected to said band, and one or more stops extending over 75 the space between the wick tubes from an adjacent part of the stove and arranged to limit the elevation of the band.

75 24. In a stove of the character described, the combination of an open top reservoir having a vertically extending wick tube and a perforated inner commingling tube extending above the wick tube, a cover removably supported by the reservoir and having an outer wick tube coöperating with the inner wick tube to form a wick space there- 80 with and also having an outer commingling tube projecting above the outer wick tube, a wick band in the space between said wick tubes, said wick band having means for limiting the height of the wick, said means being located in substantially the same horizontal plane, a plurality of wick segments interposed between said band and one of the wick tubes and vertically adjustable with 85 respect thereto, means carried by one of the wick tubes for limiting the elevation of the wick band, and means whereby said band 90 may be raised and lowered.

95 25. In a stove of the character described, the combination of a pair of wick tubes, a wick band in the space between said wick tubes, said wick band having means for limiting the height of the wick, said means being located in substantially the same horizontal plane, a plurality of wick segments 100 interposed between said band and one of the wick tubes, at least one of said segments being vertically adjustable with respect to said band, means for limiting the elevation of the wick band, and means whereby said 105 band may be raised and lowered.

110 26. In a stove of the character described, the combination of an open top reservoir having a vertical wick tube and a commingling tube extending above the wick 115

tube, a removable cover for the reservoir having a depending outer wick and a perforated commingling tube projecting above such wick tube, a wick band in the space between the wick tubes, a plurality of wick segments interposed between said band and one of the wick tubes and vertically adjustable with respect thereto, means carried by the wick band and arranged in substantially the same horizontal plane for limiting the vertical adjustment of the wick segments, and 10 a plurality of fingers carried by one of the wick tubes and overhanging the top of the wick space and adapted to limit the elevation of the wick band, and means whereby the band may be raised and lowered.

27. In a stove of the character described, the combination of a pair of wick tubes, a wick band in the space between the wick tubes, a plurality of wick segments interposed between said band and one of the wick tubes and vertically adjustable with

respect to said band, means carried by the wick band and arranged in substantially the same horizontal plane for limiting the vertical adjustment of the wick segments, and 25 a stop device adapted to limit the elevation of the wick band.

28. In an oil burner, the combination of inner and outer wick tubes, a wick therebetween comprising a plurality of wick segments, at least one of said segments being vertically adjustable whereby the vaporizing area of the top of the wick may be varied, and means whereby the wick, composed 30 of such adjustable segments, may be raised and lowered.

In testimony whereof, I hereunto affix my signature in the presence of two witnesses.

LEE S. CHADWICK.
